UNITED STATES PATENT OFFICE.

FERNE G. KEISER, OF COLUMBUS, OHIO.

TIE AND PROCESS OF MAKING SAME.

1,232,566.

Specification of Letters Patent. Patented July 10, 1917.

Application filed May 2, 1916. Serial No. 94,908.

To all whom it may concern:

Be it known that I, FERNE G. KEISER, a citizen of the United States, residing at Columbus, in the county of Franklin and State 5 of Ohio, have invented certain new and useful Improvements in and Relating to Ties and Processes of Making Same, of which the following is a specification.

This invention relates to a process of making neckwear, more particularly ties, such as 10 four-in-hand and ascots and the product resulting from such process.

One object of the invention is to provide an improved process of making a tie that is 15 durable, easily tied and capable of holding substantially its original shape, without wrinkling, rolling, stretching, disengagement or misplacement of its parts, including the tie facing.

Another object of the invention is to provide 20 an improved tie which is durable and capable of holding its original form without stretching, ripping, wrinkling or rolling.

Another object of the invention is to provide 25 a tie the parts of which are correlated and connected together in a manner which insures long use of the tie without causing substantially any deformity, rolling, wrinkling or ripping of the tie or its parts.

Another object of the invention is to provide 30 an improved tie, the parts of which are connected together to permit easy slippage of the neck band portion thereof relative to the collar of the wearer.

Other objects of my invention will be obvious 35 to one skilled in the art from the description of it hereinafter made.

My invention consists first in cutting or 40 forming, in any suitable manner, the pieces of material, to-wit, the facing, the inner lining, and the outer lining, of which the tie is made, to give the desired shape and size. The inner and outer linings correspond with 45 each other in size and shape from end to end, except, by preference, the outer lining is made somewhat longer than the inner lining. The facing is cut to the same shape as the inner and outer linings, but is somewhat wider, from end to end, than said linings 50 and preferably slightly longer than the outer lining.

These pieces of material will be cut according to the style and shape of the tie to be made. Each of said pieces of material 55 may be cut from a single length of material, or each piece may be formed from two sec-

tions of material placed end to end, for economical reasons.

Next, I place the inner and outer linings on each other or face to face and connect 60 them together by several rows of stitches extending substantially from end to end of said linings. The rows of stitches are preferably uniformly spaced from each other and the opposite outer rows of stitches are 65 positioned at points somewhat remote from the opposite longitudinal edges of the linings.

Next, I place the facing on the outer lining with its finished side thereagainst and 70 its opposite longitudinal edges conterminous with the opposite longitudinal edges of said inner and outer linings, and then I stitch the opposite longitudinal edges of all three pieces of material together, the stitches being 75 preferably arranged relatively close to the opposite longitudinal free edges of these pieces.

Next, I turn the tie right side out. By this operation I reverse the finished side of 80 the facing and position the inner lining between the facing and the outer lining.

This operation will expose the finished side of the tie and cause its opposite longitudinal edges to be folded over the opposite 85 longitudinal free edges of the linings, so that the latter will not be exposed in any way.

Next, I may press the tie by the use of a 90 pressing device, to make all parts of the tie flat, finished and perfect in form.

Finally, I stitch several longitudinal rows 95 of stitches throughout that part of the tie constituting the neck band to fasten and compress these parts of the facing, inner lining and outer lining closely together.

In carrying out my invention I provide both an inner and an outer lining, both of which extend from end to end of the tie and connect them together independently of 100 the facing at a plurality of points transversely of the tie and substantially from end to end thereof, so that when the tie is completed, all strains and stresses due to pulling and stretching of the tie in tying it 105 and rolling and deformation of the tie due to use are avoided; this insures longer life for the tie and perfect shape as long as it is worn. Again, as the tie maintains its shape, 110 it will be obvious that whenever it is cleaned and pressed, it will appear to be substantially new. Furthermore, the linings serve

to reinforce each other, thus preventing their wrinkling, rolling up or misplacement relative to the facing.

Having described the steps of my process, I will now describe ways and means for carrying out those steps and the product resulting therefrom.

Figure 1 is a top plan view of a piece of facing material of which the tie is made.

Figs. 2 and 3 are top plan views of the inner and outer linings, respectively.

Fig. 4 is a view showing the linings placed face to face and stitched together.

Fig. 5 is a view showing the facing placed on and stitched to the linings.

Fig. 6 is a view showing the facing turned right side out with the inner lining arranged between the outer lining and the facing and the tie pressed into shape.

Fig. 7 is a fragmentary bottom plan view of the tie.

Fig. 8 is a fragmentary view of the neck band portion of the tie after the same is completed.

Fig. 9 is a transverse section on the line 9-9 of Fig. 5.

Fig. 10 is a transverse section on the line 10-10, of Fig. 6.

In the drawings, 1 indicates a piece of suitable facing material, such as silk or satin, which forms the outside piece or surface of the completed tie. Preferably, this piece of fabric or material is formed of two sections cut on the bias and then stitched together end to end. The opposite outer ends of the sections may be hemmed in the usual manner, as shown at 1^a.

2 indicates the inner lining for the tie. This lining is preferably formed from some soft material, such as shaker flannel. 3 indicates the outer lining of the tie. The lining 3 is preferably formed from sateen. The inner and outer linings 2 and 3 are each preferably formed from two sections of material which are sewed together end to end in any well known manner, for economical reasons or on account of the width of the material from which the sections are formed. The inner and outer linings 2 and 3 are cut to the same size and shape, except that the outer lining may be made somewhat longer than the inner lining and substantially as long as the piece of facing material. The facing is of substantially the same shape as, but is cut somewhat wider from end to end than the linings 2, 3, so that when the tie is turned right side out, the extra width of the facing will permit it to fold over and around the opposite longitudinal free edges of the linings, as shown in Fig. 7.

The pieces of material 1, 2 and 3 are cut to the desired shape according to the style of tie, such as a four-in-hand or ascot, that is to be made up.

In constructing the tie, the inner and outer

linings are placed on top of each other or face to face and then stitched by a plurality of rows of stitches 4. The stitches 4 are substantially parallel with each other and preferably extend substantially from end to end of the linings; and the opposite outer rows of stitches are preferably arranged at points somewhat remote from the opposite longitudinal edges of the linings, as shown in Fig. 7. After the linings 2, 3, are stitched, the facing 1 is placed on top of the outer lining 3 with its finished side thereagainst and its opposite longitudinal edges substantially conterminous with the opposite longitudinal edges of the linings 2, 3, as shown in Fig. 5. The opposite edges of the linings 2, 3, and facing 1 are stitched together by stitches 4'. The stitches 4' extend from end to end of the tie as shown in Fig. 5. The extra width of the facing 1 permits it, when turned right side out, to be folded over and around the opposite longitudinal free edges of the linings to cover the edges and stitches 4' from view.

5 indicates a plurality of stitches extending longitudinally of the neck band portion of the tie. The stitches 5 extend through both the inner and outer linings 2, 3, and the facing 1, and in co-operation with the stitches 4, serve to secure the latter to the linings and the linings to each other at substantially all points throughout the length of the neck band. As a result of this construction, the neck band portion is made smooth and substantially all portions of the pieces of material constituting such band are so uniformly connected together that binding of any portion of this part of the tie in the collar of the user is avoided. The construction therefore provides for the ready slippage back and forth in the collar to adjust it during the tying operation.

By providing an inner and outer lining and connecting them together by a plurality of rows of stitches extending substantially from end to end, independent of the facing, the latter is provided with a substantial backing which insures long life for the tie and overcomes wrinkling and stretching of the tie as an entirety and of the facing. Furthermore, the construction insures strength to the tie as an entirety, so that stretching and rolling up, as well as tearing or ripping of the tie, or its facing, is entirely avoided.

My process of making ties is advantageous in that it provides each tie with inner and outer linings of a width substantially equal to the width of the front surface of the facing 1 when the tie is completed; so that no matter what part of the tie is grasped in tying it and adjusting it to the collar, the strains are entirely taken up by the linings without permitting the facing to stretch.

By stitching the opposite longitudinal

edges of both linings to each other and to the opposite longitudinal edges of the facing 1, I prevent the edges of the linings from rolling up or their misplacement relative to 5 the facing.

6 To those skilled in the art to which my invention relates, many alterations in construction and widely different embodiments of my invention will suggest themselves 10 without departing from the spirit and scope thereof. My disclosures and the description herein are purely illustrative and are not intended to be in any sense limiting.

What I claim is:

15 1. The herein described process which consists in securing together face to face two linings cut to substantially the same size, then stitching the opposite longitudinal edges of a facing material of greater 20 width than said linings to the opposite longitudinal edges of said linings with its finished face toward the linings, and then reversing said linings and said facing material.

25 2. The herein described process which consists in securing face to face an inner and an outer lining, then stitching the opposite longitudinal edges of a facing material of greater width than said outer lining 30 to the opposite longitudinal edges of said outer lining with its finished face toward the outer lining, and then reversing said linings and facing material.

35 3. The herein described process which consists in arranging face to face an inner lining and an outer lining of substantially the same shape and size, then stitching said linings together between their opposite longitudinal edges, then placing on said outer 40 lining a facing of greater width than said linings with its finished side against the outer lining and its opposite longitudinal edges substantially conterminous with the opposite longitudinal edges of said inner 45 and outer linings, then stitching the opposite longitudinal edges of the inner and outer linings and the facing together, and finally reversing the facing and outer lining.

50 4. A tie comprising inner and outer linings arranged face to face with their opposite longitudinal edges terminating in sub-

stantially the same plane, and a facing, said linings being secured together between their opposite longitudinal edges and the opposite longitudinal edges of the facing being stitched to the opposite longitudinal edges of said linings and the facing being folded over the stitches and opposite longitudinal free edges of the lining.

55 5. A tie comprising an inner lining, an outer lining, and a facing, the opposite longitudinal edges of the facing being stitched to the opposite longitudinal edges of the linings and the facing being folded over the 60 stitches and opposite longitudinal free edges of the linings, and a plurality of spaced rows of stitches connecting the linings together substantially end to end independently of the facing.

65 6. A tie comprising inner and outer linings arranged face to face with their opposite longitudinal edges terminating in substantially the same plane, and a facing, the opposite longitudinal edges of the facing 70 being stitched to the opposite longitudinal edges of the linings and the facing being folded over the stitches and the opposite longitudinal free edges of the linings, a plurality of rows of stitches connecting the linings together substantially end to end 75 independently of the facing, and a plurality of rows of stitches extending longitudinally of the neck band portion of the tie and connecting the linings and facing together.

80 7. A tie comprising an inner lining, an outer lining and a facing the material of which facing is wider throughout its length than either of said linings, the opposite longitudinal edges of the facing being stitched to the opposite longitudinal edges of the outer lining and folded over said stitches and the opposite longitudinal free edges of said outer lining, and means securing the 85 inner and outer linings together between their opposite longitudinal edges independently of the facing.

85 In testimony whereof I affix my signature, in the presence of two witnesses.
